JIB CRANE

Fredrick J. Truesdale, Steubenville, Ohio, assignor
to National Steel Corporation, a corporation of
Delaware

Application May 23, 1950, Serial No. 163,597

3 Claims. (Cl. 212—125)

1

The present invention relates to an improved crane structure and is primarily concerned with a novel crane structure for use in steel mills and other plants.

In steel mills, the molten steel is discharged from an open hearth furnace, Bessemer converter, mixer or other source into a large ladle. The ladle is then transported from one point at which the ladle is filled to the floor where the ingot molds are located. The customary mill includes a large overhead crane and this mill crane is used to transport the ladle and to support the ladle as the metal is teemed into the ingot molds. The molds may be movably supported and moved one after the other past the teeming ladle, or, the crane may be used to move the ladle from one ingot mold to the next until the ladle is empty. A pouring platform extends along the side of the building adjacent the floor where the ingot molds are located and men are stationed on this platform for aiding in the teeming operation. It is a customary practice in many mills to place caps or hot tops on the ingot molds and after the steel has solidified, these caps must be removed. The caps are quite heavy and it is necessary to use the large overhead crane to place the caps on the molds and to remove the caps from the molds after the steel has cooled sufficiently. Using the mill crane to position or remove the caps ties up the crane, prevents the crane from being used to handle the ladle, interferes with the operation of the plant and causes expensive delays.

It is an object of the present invention to provide an improved apparatus for placing caps and other objects on the ingot molds and for removing the caps that can be used without interfering with the overhead mill crane.

Another object of the present invention is to provide a novel apparatus for removing caps and other objects from ingot molds that can be readily moved out of the way of the overhead mill crane when the mill crane is transporting ladles of molten steel into position for teeming the metal into the ingot molds.

Another object of the present invention is to provide a novel crane structure arranged in such a manner that it can be swung to an operative or lifting position in which position the crane is in position to lift caps onto or off of ingot molds and is in the path of travel of at least a portion of the large overhead mill crane and mounted in such a manner that the crane structure can be folded back out of the way of the overhead crane to a non-lifting position.

2

In accordance with the present invention, upper and lower ways are mounted in spaced relation relative to each other on the side of a wall structure at the side of the mill building 5 in which the ingot floor is located where the ingot molds are filled with molten steel. The ways extend horizontally along the side of the side wall and a vertically disposed crane carriage is mounted on these ways for movement along 10 the side of the building. A boom is mounted on the carriage and extends out over the pouring or ingot floor for lifting the caps onto or off of the ingot molds and when this crane is not being used, the boom can be folded back adjacent to or 15 against the crane carriage and out of the way of the path of the large overhead crane so that the overhead crane can move into position with a ladle of hot steel to team the metal into the ingot mold. The foldable crane structure does 20 not interfere with normal operation of the large overhead crane which is used for many purposes and prevents costly delays in the various mill operations.

These and other objects and advantages of 25 the present invention will become more readily apparent from the following description, taken in connection with the accompanying drawings, in which:

Figure 1 is a side view, partially in section, 30 showing apparatus embodying the principles of the present invention; and

Figure 2 is a front view of a portion of the apparatus shown in Figure 1.

Referring to the drawings, the building 10, only 35 a portion of which is shown, may be of any suitable type, and includes a vertical, outer side wall 11. As shown, a series of vertical structural members 12 are located adjacent to and inside of side wall 11. These vertical structural members 12 constitute an upright side wall structure 13 supporting an upper horizontal beam 14. This side wall structure 13 may be a separate wall structure, as shown, or may form part of the side wall of the building 10. The horizontal beam 45 14 carries a long horizontal rail 16. A large overhead crane 17 is mounted on rail 16. A side wall structure similar to 13 supporting a second rail like rail 16 is provided at the opposite side of the building. The second rail and its supporting structure have not been shown as they 50 are the same as shown.

The large overhead crane 17 is customarily provided in the buildings of steel mills and this crane is intended to transport heavy loads such 55 as a ladle from one location to another location

in the building. The crane 17 carries a depending cab 15 in which the crane operator is located. The crane 17 is used to transport a ladle filled with molten steel and to support the ladle while the molten metal is teemed into the ingot molds 19 located in the area of the mill commonly referred to as the ingot floor. A platform 20 is provided at the side of the building and workmen usually stand on this platform 20 in position to aid in carrying out the teeming operation. It is frequently necessary to place caps 18 on top of the ingot molds 19 and then to remove the caps from the molds. These caps are quite heavy and it has been customary to use the crane 17 to lift the caps and place them on the molds and to remove the caps from the molds. This ties up the crane 17 and prevents the crane from being used at other places in the mill building and prevents the crane from being used to transport full or empty ladles of molten metal. This in turn reduces the amount of steel produced as other operations must wait until the crane 17 is available.

As described heretofore in detail, the mill structure, the crane, the ingot molds and the other equipment are of customary construction.

In accordance with the present invention, a novel crane apparatus is provided for lifting caps to remove or emplace the caps or other objects on the ingot molds. As will be more fully described in detail, this crane is arranged in novel manner so as not to interfere with the use of the mill crane 17.

On the sides of columns 12, there are mounted lower and upper brackets 22 and 23. The lower brackets carry a beam 25 on which is mounted a lower way or rail 26 extending along the wall 13. The upper brackets 23 support a pair of horizontally spaced apart guides 27 which together provide an upper way or guide slot 28. A crane 29 is mounted on the side of the wall structure 13 for horizontal movement along the ways 27 and 28 and along the side of the upright wall 13.

The crane 29 includes a rectangular carriage frame 30 provided with lower flanged wheels 31 that ride on rail 26. A pair of vertical upper guides or rolls 32 are rotatably mounted in bearings 33 and these guides 32 extend between guide members 27 for holding the carriage 29 upright as it moves along the rail 26. A boom 35 is pivotally mounted at the inner end in bearings 36 and can be positioned in a load lifting position in which the boom extends outwardly away from the carriage 29 as shown in full lines in Figure 1. The boom 35 is swingable from the load lifting position and can be folded upwardly back against the carriage 29 as shown in full lines in Figure 2 and as shown in broken lines in Figure 1.

A motor driven boom hoist 36 is mounted on the carriage frame 30 and a cable 37 is connected to the outer end portion of the boom 35. The cable 37 passes around a pulley 38 at the top of the carriage and down to the hoist 36. The hoist 36 can be operated to reel in or pay out cable 37 and raise or lower the boom. A second motor driven hoist 39 is mounted on frame 30. A cable 40 extends from hoist 39 and over a sheave 40' on the outer end of the boom. The end of cable 40 carries a load engaging and lifting tool 41. Hoist 39 can be operated to reel in or pay out cable 40 and lift or lower an ingot cap or other article. An electric motor 42 is mounted on carriage frame 30 and connected

to one of the wheels 31 for moving the crane 29 along the ways and along the side of the wall 13. A control panel 44 is mounted on the crane 29 and includes the necessary control means for operating the hoists 36 and 39 and motor 42. Preferably, the panel 44 is located so that an operator standing on the escape platform 45 can reach the panel and operate the crane 29. The platform 45 is provided to facilitate the escape of the operator of crane 17 from cab 15. The panel 44 may be located at any suitable point, a preferred location being shown. A safety cable 46 is connected to the boom and carriage.

Assuming that the crane 29 is being used and that crane 17 is at some other location in the mill, the boom 35 is in the load lifting position and extends outwardly from the carriage. The crane is used to lift caps or other objects off of or onto the ingot molds. The mill crane 17 can be used at other locations and is not tied up by this operation. When the crane is to bring a ladle of metal to the ingot floor for teeming molten steel into the ingot molds, it will be noted that the cab 15 moves in a path along the side of the building adjacent the side wall 13 and that the outwardly extending boom 35 is in the path of a portion of the crane 17. Before the crane 17 is moved into position over the ingot molds, the hoist 36 is operated to fold the boom 35 upwardly toward and preferably up against the carriage 30 and out of the path of crane 17. The crane 17 is then moved over the ingot molds to fill the molds. After the crane 17 has been moved along the building to return the empty ladle to be filled or has been moved from above the ingot molds for any other purpose, the crane boom 35 can be lowered back to the operating or load lifting position.

With the present arrangement, the mill crane 17 which is used for many purposes around the mill, is not tied up to lift the ingot mold caps 18 and the crane boom 35 can be folded back out of the way of crane 17 when it is necessary to move crane 17 past crane 29. The crane carriage is disposed in a vertical plane and is movable along the upper and lower ways so that carriage 29 does not extend out over the mill floor and into the path of crane 17.

I claim:

1. A crane structure comprising an upright, horizontally elongated wall structure including vertical supporting members, a horizontal lower rail mounted on the supporting members, laterally spaced apart horizontal guide members disposed above the lower rail and mounted on the vertical supporting members, a crane carriage disposed in a vertical plane, the crane carriage including flanged wheels mounted on the lower rail and rollers extending between the guide members so that crane carriage is movable along the side of the wall structure, a motor connected to the flange wheels for moving the carriage along the rail, a first hoist mounted on the carriage, a second hoist mounted on the carriage, a boom pivotally mounted at one end on the crane carriage, a boom supporting cable connected to the first hoist and to the boom for supporting the boom in a lifting position in which the boom extends outwardly from the carriage and for folding the boom inwardly toward the carriage to a folded position, and a load lifting cable connected to the second hoist and carried by the boom for lifting an object.

2. A crane structure comprising an upright wall structure including vertical supporting

members, a horizontal relatively lower way means mounted on the supporting members, a horizontal relatively higher way means mounted on the supporting members, a carriage mounted on the way means and movable therealong, motor driven drive means mounted on the carriage and operable to move the carriage along the way means, a first hoist mounted on the carriage, a second hoist mounted on the carriage, a boom pivotally mounted at one end on the carriage and swingable about a horizontal axis, a boom supporting cable connected at one end to the boom and connected at the other end to the first hoist for supporting the boom in a lifting position in which the boom extends outwardly from the carriage and for folding the boom upwardly and inwardly toward the carriage to a folded position, and a load lifting cable connected to the second hoist and carried by the boom with the second hoist being operable to reel in and pay out the load lifting cable to raise and lower an object.

3. A crane structure comprising an upright wall structure including laterally spaced apart vertical supporting members, horizontal lower rail means mounted on the supporting members, horizontal guide means mounted on the supporting means spaced from and substantially directly above the lower rail means, a rectangular crane carriage means disposed between the rail means and the guide means, the crane carriage means including flanged wheels mounted on the lower

5 rail means and roller means engaging the upper guide means so that the carriage is movable along the side wall of the structure, motor means connected to the flanged wheels for moving the carriage along the wall structure, a boom pivotally mounted at an inner end on the carriage and extending outwardly from the carriage, the boom being swingable about a horizontal axis, a first hoist means mounted on the carriage, a supporting cable connected at one end to the boom and connected at the other end to the first hoist, the supporting cable supporting the beam in its outwardly extending, lifting position, the first hoist means being operable to reel in the boom supporting cable and swing the boom upwardly and inwardly toward the carriage, a second hoist means mounted on the carriage, and a load lifting cable connected at one end to the second hoist means and extending over sheave means at the outer end of the boom for raising and lowering an object.
